GRATED VAULT COVER

Emil A. Altobello, 555 Preston Ave.,
Meriden, Conn. 06450

Filed Apr. 19, 1971, Ser. No. 135,520

Term of patent 14 years

Int. Cl. D25—02

U.S. Cl. D60—2

FIG. 1

FIG. 1 is a top plan view of the grated vault cover.

FIG. 2 is a bottom plan view of the cover shown in FIG. 1.

FIG. 3 is a front elevation view of the cover shown in FIG. 1.

FIG. 4 is an enlarged sectional view of the cover as seen along the sectioning line 4—4 of FIG. 1.

FIG. 5 is an enlarged side elevation view of the cover partially broken away to show the cover along the sectioning line 5—5 in FIG. 1.

I claim:

The ornamental design for a grated vault cover, as shown and described.
